(57) **CLAIM**

The ornamental design for an eyewear viewing device, as shown and described.

DESCRIPTION

FIG. 1 is a perspective view of an eyewear viewing device, according to the present design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a rear top perspective view thereof;

FIG. 9 is a rear bottom perspective view thereof;

FIG. 10 is a rear view without the prescription lens insert;

FIG. 11 is a rear view with transparent lenses and with the prescription lens insert; and,

FIG. 12 is a rear view of FIG. 11 without the prescription lens insert.

The broken lines in the drawings illustrate portions of the eyewear viewing device and form no part of the claimed design.

1 Claim, 8 Drawing Sheets
